CYCLOMETER CLOCK ALARM

Lucien C. Wuischpard, Long Hill, Conn., assignor
to Casco Products Corporation, Bridgeport,
Conn., a corporation of Connecticut

Application November 21, 1947, Serial No. 787,419

13 Claims. (Cl. 58-18)

1

This invention relates to switching or control mechanisms for use with cyclometers or like devices, and more particularly to an alarm mechanism for a cyclometer clock.

While the invention is illustrated in connection with an electric clock of the direct-reading or cyclometer-type, for controlling the alarm device thereof, it should be understood that the invention is not to be limited to clocks or to the specific embodiment thereof shown herein, since it has utility in connection with cyclometer devices generally, wherein related relatively movable members or counters are provided, usually having different rates of advance.

An object of the invention is to provide, for a cyclometer device or cyclometer clock, an improved settable alarm control or switching mechanism having but a single manually operable member settable by a simple continuous movement, which mechanism is extremely simple in construction with very few and inexpensive parts, and is economical in assembly while at the same time being very reliable in operation, thereby to effect advantageous economies in manufacture while maintaining high quality.

Another object of the invention is to provide an improved alarm or control mechanism as above which is rugged and sturdy in construction, and the operativeness of which is not adversely affected during setting of the cyclometer device, however the counters thereof may be manipulated.

A further object of the invention is to provide an improved and simplified switching or alarm control mechanism of the above type, which is extremely compact and small in size so that it requires but very little space.

Still another object of the invention is to provide a simplified and reliable switching or alarm control mechanism as above which does not require extensive modification or changing of the parts of the cyclometer device in adapting it for use with said mechanism.

A feature of the invention is the provision of simple means, in a switching or control mechanism as above, whereby the mechanism may be used with a cyclometer-type clock having hour and tens-of-minutes wheels each provided with twelve indicia whereby they may be of substantially the same size, the indicia on the tens-of-minutes wheel consisting of two sets of six indicia each.

In accomplishing the above objects there is provided, in accordance with the invention, elements in the form of contacts which are respec-

2

tively settable each in different positions to sense any desired one of a plurality of different relative wheel positions of a clock. The elements or contacts are preferably mounted so as to be rotatable independently of each other about the same axis. There is also provided a member which is manually settable in different positions, the member being preferably in the form of a dial having graduations on it indicating ten-minute intervals throughout a twelve hour period, and the dial having numbers from 1 through 12 indicating the respective hours. Gear means are provided between the manually settable dial and the settable elements or contacts whereby the latter are coupled to the dial in different ratios respectively. For example, one element may be connected to the dial by gears having 1 to 6 ratio, and another element may be connected to the dial by gears having a 1 to 1 ratio. Cooperating with the settable elements or contacts are other contacts which are positioned by the wheels of the clock, and the arrangement is such that when the wheels attain the relative positions determined or indicated by the setting 25 of the manually settable dial the cooperating contacts engage each other, thereby closing a circuit and causing the alarm to be sounded.

One of the pairs of contacts which cooperate with each other extends in an arc which, in the particular embodiment of the invention illustrated herein, is approximately 30°, so that engagement occurs between these cooperating contacts for a predetermined number of different relative positions thereof; these cooperating contacts are associated with the hour wheel of the clock and enable an alarm to be sounded for different ten-minute intervals within an hour period without requiring movement of the hour wheel. Other contacts which are associated with the tens-of-minutes wheel, are disposed at several arcuately spaced points about the common axis of the contacts, thereby to provide for contact engagement more than once in each revolution of the tens-of-minutes wheel, enabling the wheel to have duplicate sets of indicia and thereby to have a total number of indicia equal to the number provided on the hour wheel, so that both wheels may be the same size.

The gearing between the settable dial and the settable contacts provides for automatically locating the contacts to sense the desired one of the plurality of different relative positions of the wheels as indicated by the setting of the dial.

Other features and advantages will hereinafter appear.

In the accompanying drawings:

Figure 1 is an axial sectional view of the improved switching or control mechanism of the invention, and of a cyclometer type clock in which the mechanism is incorporated.

Fig. 2 is an elevational view of the mechanism looking from the left-hand end of Fig. 1.

Fig. 3 is a fragmentary transverse section taken on line 3-3 of Fig. 1.

Fig. 4 is a fragmentary sectional view taken on line 4-4 of Fig. 2.

Fig. 5 is a schematic circuit diagram of the alarm and control mechanism of the invention, and

Figs. 6, 7, 8 and 9 are diagrams showing the relations of the manually operable dial of the mechanism and the sensing elements or contacts operated by said dial, and also the contacts co-operable with the sensing contacts for controlling an electrical circuit. Fig. 6 shows the positions for an alarm sounding at 7:00 o'clock; Fig. 7 shows the positions for an alarm sounding at 7:10 o'clock; Fig. 8 shows the positions for an alarm sounding at 7:30 o'clock; and Fig. 9 shows the positions for an alarm sounding at 8:00 o'clock.

Referring to Figs. 1 and 2, the clock and alarm control mechanism of the invention comprises a frame 10 having an upstanding end portion or wall 11 which is apertured to receive an outer sleeve 12, an inner sleeve 13 extending through and bearing in the outer sleeve 12, and a shaft 14 extending through and bearing in the inner sleeve 13. The outer sleeve 12 is rotatable in the wall 11 of the frame, and the shaft 14 has a reduced end portion 14a which passes through and rotatably bears on a plate 15 secured by studs 16 to the wall 11 in spaced relation therewith.

The shaft 14 has rotatable thereon a "minute" wheel 17, the inner sleeve 13 has rigidly secured to it a "tens-of-minutes" wheel 18, and the outer sleeve 12 has rigidly secured to it an "hour" wheel 19, the wheels 17, 18 and 19 being independently rotatable but having their movements related by any suitable means, and the wheels having indicia 20 on their peripheries to enable them to indicate time. A carry-over mechanism suitable for use with the wheels 17, 18 and 19 to correlate their movements is disclosed and described in detail in my copending patent application S. N. 702,983 filed October 12, 1946, now Patent No. 2,549,556 granted April 17, 1951, and therefore such mechanism will not be described herein as it specifically forms no part of the present invention.

The hour wheel 19 may have twelve flat faces 21 located about its periphery and numbered consecutively from 1 through 12, and the tens-of-minutes wheel 18 may also have twelve faces 22 about its periphery, numbered consecutively from 0 through 5, the numbers being duplicated or repeated once so that there are two sets of such numbers. It will be understood that the tens-of-minutes wheel 18 is advanced $\frac{1}{2}$ of a revolution at the end of each ten-minute interval, to present the next number or indicia to view, and that each time the wheel 18 moves to present a zero (0) to view (which is twice in each revolution) it advances the wheel 19 through $\frac{1}{2}$ of a revolution to cause the next or succeeding indicia on the wheel 19 to be presented to view, as is usual in cyclometer-type clocks.

According to the present invention a novel settable control or switching mechanism is provided in conjunction with the wheels 18 and 19 whereby a circuit may be switched or an alarm sounded when the wheels reach any desired one of a plu-

rality of different relative rotatable positions. This novel mechanism includes a manually operable dial 23 having a finger-engageable slot 24 in its outer face, the dial extending through the clock casing 25 (which is secured to the frame 10 in any suitable manner not shown).

Referring to Figs. 2 and 6 through 9, the dial 23 has graduations 23a some of which are provided with numbers 26 from 1 through 12, the intervals between adjacent numbered graduations being divided each into six equal spaces by five unnumbered graduations, each of said five graduations indicating a ten-minute interval. Thus, the dial 23 may be set for any ten-minute interval throughout a twelve-hour period of time.

The dial 23 has a hub 27 provided with a square recess for receiving the square end portion 28 of a shaft 29 which passes through the plate 15 and wall 11 of the frame 10 and rotatably bears on said plate and wall. Between the plate 15 and wall 11 the shaft 29 carries a pair of gears 30 and 31, the gear 30 meshing with a pinion 32 which forms part of a collar 33 rotatable on the reduced end portion 14a of the shaft 14. The ratio between the gear 30 and pinion 32 is six-to-one, so that for each revolution of the dial 23 the pinion 32 and collar 33 is made to revolve six times. The gear 31 meshes with a gear 34 forming part of a collar 35 rotatably carried on the inner sleeve 13, which latter projects beyond the end of the outer sleeve 12. The ratio of the gear 31 to the gear 34 is one-to-one. Between the collars 33 and 35 a collar 36 is provided, rigidly secured to the inner sleeve 13, and a collar 37 is mounted on and rigidly secured on the outer sleeve 12 adjacent the opposite side of the collar 35.

The collars 33, 35, 36 and 37 are preferably formed of insulating material, and the collar 33 has attached to it a metal sleeve or band 38 having a flange 39 from which are lanced two resilient contact arms 39a, the extremities 39b of the arms being dished or cupped to present convex faces to the right as shown in Fig. 1. The collar 36 has an integral insulating flange 40 for engagement with the dished portions 39b of the resilient arms 39a, and has rigidly secured to it a metal band 41 provided with two resilient contact arms 42 having end portions 43 which extend through slots or cuts in the flange 40 and are adapted to engage and make electrical contact with the resilient arms 39a when in alignment with the dished portions 39b thereof. The collar 35 has rigidly secured to it a metal band 44 having a flange 45 from which is lanced a single resilient contact arm 45a, the end portion 45b of which is dished and presents a convex face to the right as shown in Fig. 1, and the collar 37 has rigidly secured to it a metal band 46 provided with a resilient arm 47 extending radially therefrom and having an extremity 47a passing through a slot in an insulating flange 48 which is integral with the collar 37. The flange 48 and extremity 47a are located for engagement with the resilient contact arm 45a, and when the portion 45b thereof is in alignment with the extremity 47a of the arm 47 electrical contact will be established between the arms, as shown in Fig. 1. Electrical contact is made to the bands 38, 41, 44 and 46 by spring wire clips 49, Figs. 1 and 2, the said clips having portions 49a embracing opposite peripheral surfaces of the bands, and the clips being carried on a bushing 50, Figs. 2 and 4, mounted between the plate 15 and wall 11 by one of the studs 16. The bushing 50 is preferably formed of insulating material, and has metal inserts 51, 52

and 53, the insert 52 electrically connecting together the two inner-wire clips 49. An outer wire clip 49 is electrically connected by the insert 51 with a metal-terminal eyelet 54 which is secured to a lead wire 55, and the other outer-wire clip 49 is electrically connected by the insert 53 with a metal-terminal eyelet 56 secured to a lead wire 57.

The operation of the switching or control mechanism of this invention may be best understood by referring to Figs. 6 through 9 in connection with Figs. 1 and 2. In Figs. 1 and 2 the wheels 18 and 19 are positioned so that the numbers 0 and 7 (not shown) respectively of said wheels are on a level with the shaft 14 and may be viewed through the window 25a of the clock casing 25, indicating sometime between 7:00 o'clock and 7:10 o'clock, such position being evident by virtue of the fact that the numbers 5 and 6 of the hour wheel 19 are shown below the shaft 14 and the numbers 4 and 5 of the tens-of-minutes wheel 18 are also shown below the shaft 14 in such sequence that the succeeding numbers 7 and 0 will be level with the shaft and at the casing window 25a. These positions of the parts may correspond with the positions of the diagrammatic showing in Fig. 6, wherein the manually operable dial 23 is illustrated as being set on 7:00 o'clock. For this setting of the dial, the resilient contact fingers 39a are so located that the dished contact portions 39b thereof lie centralized in the vertical plane through the shaft 14. Also, the resilient contact arm 45a is so disposed that the dished contact portion 45b thereof is located vertically above the shaft 14, and the extremities 43 of the resilient contact arms 42 are located vertically and opposite the portions 39b of the arms 39a.

As shown in Figs. 6 through 9 the contact portions 43 of the arms 42 are preferably of segmental shape, although they need not necessarily be so, and extend through arcs of approximately 30°. Likewise the contact portion 47a of the resilient arm 47 is of segmental shape, and extends through an arc of 30°. However, as seen in Fig. 6, the segmental portion 47a of the contact arm 47 is not located directly or vertically above the shaft 14 but instead to the right of the shaft, the left-hand edge of the contact extending approximately one or two degrees to the left of the vertical plane through the shaft. For this condition an electrical connection will be effected between the lead wires 55 and 57, since the arms 39a engage the arms 42, and the arm 45a engages the arm 47, and referring to Fig. 5, when the said wires are connected in circuit with an alarm 58 and supply 59, and a wire 60, the alarm 58 will be sounded, and such alarm will continue to sound until the electrical connection between the wires 55 and 57 is broken. This connection will be broken after a ten-minute interval by movement of the tens-of-minutes wheel 18 when it advances the number 1 (not shown) to the window 25a in place of the number 0 (not shown). This advancing movement of the wheel 18 will cause the contact 43 to move from left to right as viewed in Fig. 6 through an arc of 30° whereupon it will become disengaged from the co-operable contact arm 39a.

It will be noted that just prior to 7:00 o'clock the wheel 18 will be showing the number 5 at the window 25a, the said number being on a level with the shaft 14, and for this position the contact 43 will be in a position shifted 30° to the left from that shown in Fig. 6, wherein it will not be in engagement with the contact arm 39a. There-

fore no circuit will be established between the wires 55 and 57 and the alarm will not be sounded, but will only be sounded after the wheel 18 has shifted so as to show the number 0 through the window 25a.

Figs. 7, 8 and 9 show alarm settings for 7:10 o'clock, 7:30 o'clock and 8:00 o'clock respectively. Considering Fig. 7, when the dial 23 is set for 7:10 o'clock, it has been shifted counterclockwise 5° from the setting of Fig. 6. This shifting causes the contact arms 39a to be shifted in a clockwise direction 30° due to the 6 to 1 ratio of the gear 30 and pinion 32. Also, the shifting of the dial 23 to 7:10 o'clock will cause the resilient contact arm 45a to be shifted clockwise 5° from the position of Fig. 6 to the new position shown in Fig. 7. With the new positions of the contact arms 39a and 45a no alarm will be sounded when the wheels 18 and 19 indicate 7:00 o'clock, since for such condition the arms 39a will not be positioned for engaging the arms 42 on account of the contact portions 43 of the latter lying in the vertical plane. However, when the tens-of-minutes wheel 18 is moved so that it shows the number 1 through the window 25a, this will cause the contacts 43 to assume the positions shown in Fig. 7 wherein they will now engage the co-operable contact arms 39a, thereby completing the circuit between the wires 55 and 57 and rendering the alarm operable. When the wheel 18 again advances, to present the number 2 in the window 25a, the contacts 43 will be advanced clockwise another 30° whereupon they will be disengaged from the arms 39a, rendering the alarm 58 inoperative.

Considering Fig. 8, when the dial 23 is set for 7:30 o'clock by shifting it counterclockwise 15° from the position of Fig. 6, it will result in the contact arms 39a being shifted clockwise 90° from the position of Fig. 6, due to the 6 to 1 ratio of the gear 30 and pinion 32. Also, it will cause the contact arm 45a to be shifted clockwise 15° from the position of Fig. 6. Following the explanation in connection with Fig. 7, an alarm will be sounded when the wheel 18 advances the number 3 to the window 25a and the alarm will cease to function when the wheel 18 advances the number 4 to the window 25a.

Referring to Fig. 9, when the dial 23 is set for 8:00 o'clock by shifting it counterclockwise 30° from the position of Fig. 6, it will cause a 180° clockwise shifting of the contact arms 39a, and a 30° clockwise shifting of the contact arm 45a. For such positions of the parts, an alarm will be sounded when the wheels 18 and 19 indicate 8:00 o'clock wherein they position the contacts 43 and 47a as shown in Fig. 9, to cause these to engage the co-operable contacts 39a and 45a respectively.

It will be seen that the switching or control mechanism as provided by this invention thus accomplishes an alarm control when used in conjunction with a cyclometer-type clock, with the provision of but very few components or parts, and with the use of but a single manually settable member or dial. While the contact 47a is shown as being of segmental shape and the dished portion of the contact arm 45a shown as being in the form of a button, it should be understood that the contact 47a may be in the form of a button and the arm 45a may have a segmental-shaped contacting portion without changing the operation of the switching mechanism as provided by the invention. It is merely necessary that one or the other of the contacts 45b and 47a which are associated with the hour wheel 19

extends arcuately a sufficient distance to enable these contacts to engage each other for all settings of the dial 23 which involve any single hour, as for example, all settings between 7:00 o'clock and 7:50 o'clock inclusive, or all settings between 8:00 o'clock and 8:50 o'clock inclusive, etc. This is necessary in order for an alarm to be sounded for any one of such settings without requiring movement of the hour wheel 19; it is understood of course that for any single hour interval the clock mechanism does not move the hour wheel 19.

Thus, where the hour wheel 19 has twelve indicia, the arcuate extent of the segmental-shaped contact should be twelve divided into 360°, or 30°. If the hour wheel 19 were to have twenty-four indicia, the segmental-shaped contact should extend for an arc of 360° divided by twenty-four, or 15°. Thus it is seen that the arc of the segmental-shaped contact should be equal to 360° divided by the number of indicia on the hour wheel 19.

The ratio of the gear 30 and pinion 32 between the dial 23 and the settable contacts associated with the tens-of-minutes wheel 18 is determined by the number of indica carried by the wheel 18. Where the number of such indicia is twelve, as in the present instance, the ratio of the gear 30 to the pinion 32 will be seventy-two divided by twelve, or six-to-one. If the number of indicia on the tens-of-minutes wheel 18 were to be six instead of twelve, the ratio of the gear to the pinion 32 would be seventy-two divided by six, or twelve-to-one. If the number of indicia on the tens-of-minutes wheel were to be eighteen, the ratio of the said gears would be seventy-two divided by eighteen, or four-to-one. This is because the extent of each movement of the tens-of-minutes wheel 18 is dependent on the number of indicia carried by it; if the wheel has twelve indicia it will move through $\frac{1}{12}$ of a revolution, or 30°, and if the wheel has six indicia it will move through $\frac{1}{6}$ of a revolution, or 60°. In each case, the ratio between the dial 23 and the contacts 39a operated by the dial should be such that when the dial is moved one graduation, corresponding to a ten-minute interval, the contacts 39a should be moved through an arc equivalent to that which the tens-of-minutes wheel 18 will move in indicating the next ten-minute interval, and this ratio is found to be seventy-two (the number of ten-minute graduations on the dial 23) divided by the number of indicia on the tens-of-minutes wheel 18, assuming of course that the graduations 23a on the dial 23 extend completely around the periphery of the dial and cover the entire 360° field. If the graduations were made to extend through only 180° of the dial 23 so that the remainder of the dial were blank, this would naturally require that the ratio of the gear 30 to the pinion 32 be doubled, in following the above analysis. Therefore, where the dial 23 may not be completely filled with graduations, the ratio of the gear 30 to the pinion 32 will be equal to seventy-two divided by the number of indicia on the tens-of-minutes wheel, and multiplied by the quotient of 360° divided by the arc, in degrees, covered by the graduations, or 25,920 divided by the product of the number of indicia on the wheel 18 times the angle covered by the graduations on the dial 23.

The ratio of the gear 31 to the gear 34 should be equivalent to the ratio between the arc, in degrees, covered by the arcuate-shaped contact associated with the hour wheel 19 and the arc, in degrees, between any adjacent pair of num-

bers on the dial 23. Since the arc between the adjacent numbers is 30°, and the arc of the segment-shaped contact is 30° for an hour wheel having twelve indicia as shown, the ratio between the gears 31 and 34 will be one-to-one. If the arc between the adjacent numbers on the dial 23 were to be 15° while the arc of the segment-shaped contact were to be 30°, then the ratio between the gears 31 and 34 would be 2 to 1. The above presupposes that the hour wheel 19 has twelve indicia; if the number of indicia on the hour wheel 19 is altered, this alters the arc of the segment-shaped contact associated with the hour wheel. However, the ratio of the gears 31 and 34 would still be determined according to the ratio between the arc of the contact and the arc included between adjacent numbers on the dial 23.

The parts of the switching mechanism as illustrated are of simple and rugged construction, and permit of easy assembly while at the same time providing for reliable operation. The spring tension between the cooperable contacts, and between the metal bands and the spring wire clips 49 may be so adjusted so as to provide for effective electrical connection and yet cause very little friction, resulting in but very slight drag on the wheels 18 and 19. Also, by virtue of the little friction existing between the contact arms and spring wire clips, the setting of the dial 23 may be accomplished very easily and quickly.

Variations and modifications may be made within the scope of this invention and portions of the improvements may be used without others.

I claim:

35. 1. In a cyclometer having a pair of related, relatively and independently movable counters adapted to indicate, by virtue of their different relative positions, a predetermined fixed and definite plurality of different conditions; a stationary member and a manually settable selector member having a range of effective movement of not more than 360° relative to said stationary member, one of said members having solely one index mark and the other of said members having graduations over an arc equal to the arc of movement of the movable member and cooperable with the index mark, said members being disposed at a locale different from the counters and said graduations corresponding respectively to all said predetermined relative positions of the counters; elements respectively settable each in different positions to sense any desired set of counter positions; means for gearing said elements to said selector member in different ratios respectively; and means including cooperating elements respectively independently positioned by said counters for switching an electrical circuit when the counters come to the particular set of positions determined by the setting of said selector member.
60. 2. A cyclometer-type alarm clock comprising an hour wheel having indicia thereon designating hours; a tens-of-minutes wheel having indicia thereon; contacts respectively settable each in different rotative positions to sense any desired one of a predetermined, fixed, maximum plurality of different relative wheel positions; a member manually settable in different rotative positions within a single arc of 360°, said rotative positions corresponding to all said relative wheel positions; means for gearing said member to said contacts in different ratios respectively; and means including contacts respectively cooperating with said settable contacts and positioned by said wheels for switching a circuit to cause an

alarm to be given when the wheels come to the particular set of positions determined by the setting of the manually-settable member, at least one of the contacts which cooperate with each other extending in an arc approximately equal to 360° divided by the number of indicia on the said hour wheel.

3. A cyclometer-type alarm clock comprising an hour wheel having a single set of indicia thereon designating hours; a tens-of-minutes wheel having two sets of indicia thereon, each set consisting of numbers from zero to five; contacts respectively settable each in different rotative positions to sense any desired 10-minute interval in 12 hours; a member manually settable in 72 different rotative positions within a single 360° arc, corresponding to said 10-minute intervals; means for gearing said member to said contacts in ratios of six-to-one and one-to-one respectively; and means including contacts respectively cooperating with said settable contacts and positioned by said wheels for switching a circuit to cause an alarm to be given when the wheels come to the particular set of positions determined by the setting of the manually settable member.

4. A cyclometer-type alarm clock comprising an hour wheel having a single set of indicia thereon designating hours; a tens-of-minutes wheel having at least one set of indicia thereon consisting of numbers from zero to five; contacts respectively settable each in different rotative positions to sense any desired one of a plurality of different relative wheel position; a member manually settable in different rotative positions; means for gearing said member to said contacts in ratios of one-to-one and X to one where X equals 72 divided by the number of indicia on the tens-of-minutes wheel; and means including contacts respectively cooperating with said settable contacts and positioned by said wheels for switching a circuit to cause an alarm to be given when the wheels come to the particular set of positions determined by the setting of the manually settable member, at least one of the contacts which cooperate with each other extending in an arc approximately equal to 360° divided by the number of indicia on the said hour wheel.

5. A cyclometer-type alarm clock comprising an hour wheel having a single set of indicia thereon designating hours; a tens-of-minutes wheel having at least one set of indicia thereon consisting of numbers from zero to five; contacts respectively settable each in different rotative positions to sense any desired one of a plurality of different relative wheel positions; a member manually settable in different rotative positions; means associated with said member, providing seventy-two arcuately disposed graduations to enable the member to be set in any one of seventy-two different rotative positions, means for gearing said member to said contacts in ratios of one-to-one and X to one where X equals 25,920 divided by the product of the number of indicia on the tens-of-minutes wheel times the arc, in degrees, through which said graduation means extends; and means including contacts respectively cooperating with said settable contacts and positioned by said wheels for switching a circuit to cause an alarm to be given when the wheels come to the particular set of positions determined by the setting of the manually settable member, at least one of the contacts which cooperate with each other extending in an arc approximately equal to 360° divided by the number of indicia on the said hour wheel.

6. A cyclometer-type alarm clock comprising an hour wheel having indicia thereon designating hours; a tens-of-minutes wheel having at least one set of indicia thereon consisting of numbers from zero to five; contacts respectively settable each in different rotative positions to sense any desired one of a plurality of different relative wheel positions; a member manually settable in different rotative positions; means associated with said member, providing seventy-two arcuately disposed graduations to enable the member to be set in any one of seventy-two different rotative positions, means including contacts respectively cooperating with said settable contacts and positioned by said wheels for switching a circuit to cause an alarm to be given when the wheels come to the particular set of positions determined by the setting of the manually settable member, at least one of the contacts which cooperate with each other extending in an arc approximately equal to 360° divided by the number of indicia on the said hour wheel; and means for gearing said member to said settable contacts in respective ratios of (1) the arc of the arcuately extended contact to the arc included between adjacent numbers on the said graduation means, and (2) X to one, where X equals 25,920 divided by the product of the total number of indicia on the tens-of-minutes wheel times the arc in degrees through which said graduation means extends.

7. A cyclometer-type alarm clock comprising an hour wheel and a tens-of-minutes wheel axially aligned with each other and adapted to have 72 different relative rotative positions; telescoping shafts carrying said wheels; contacts respectively settable each in different rotative positions about said shafts to sense any desired one of a plurality of different relative wheel positions, said contacts being located adjacent an end of one of said wheels; a member manually settable in 72 different rotative positions within a single 360° arc, corresponding with said relative rotative positions of said wheels; means for gearing said member to said contacts in different ratios respectively; and means including contacts respectively cooperating with said settable contacts and fixed respectively to the shafts of said wheels to be positioned thereby, for causing an alarm to be given when the wheels come to the particular set of positions determined by the setting of the manually settable member.

8. An cyclometer-type alarm clock comprising an hour wheel having 12 numbers and a tens-of-minutes wheel having duplicated sets of numbers, a pair of contacts respectively settable each in different rotative positions to sense any desired one of 72 different relative wheel positions; a member manually settable in 72 different rotative positions contained in a single arc of 360° ; means connecting said member to said contacts to adjustably move the latter at different rates respectively; and means including a contact, and a plurality of contacts electrically joined and mechanically fixed to each other, respectively positioned by said wheels for causing an alarm to be given when the wheels come to the particular set of positions determined by the setting of the manually settable member, said contact and plurality of joined contacts respectively cooperating with the settable contacts of the said pair.

9. A cyclometer-type alarm clock comprising an hour wheel having 12 numbers and a tens-of-minutes wheel having duplicated sets of numbers, a contact; a pair of contacts electrically joined

and mechanically fixed to each other, said contact and pair of contacts being respectively settable in 72 different rotative positions to sense any desired one of 72 different relative wheel positions; a member manually settable in 72 different rotative positions contained in a single 360° arc; means connecting said member to said contact and plurality of contacts to adjustably move the latter at different rates respectively; and means including contacts respectively cooperating with said contact and pair of contacts and positioned by said wheels for causing an alarm to be given when the wheels come to the particular set of positions determined by the setting of the manually settable member.

10. In a mechanism for controlling an instrumentality, a cyclometer having a pair of related, relatively and independently movable counters adapted, by virtue of different relative positions, to indicate a predetermined fixed and definite plurality of different conditions; elements respectively settable each in different positions to sense by their relative positions any desired one of said plurality of different relative counter positions; a rotatable member manually settable in different positions all within a single 360° arc to correspond to all of said relative counter positions; means connecting said member to said elements to adjustably move the latter at different rates respectively; and means including other elements respectively cooperating with said settable elements and including means independently positioning said other elements respectively by said counters for exercising a control over said instrumentality when the counters and other elements come to the particular set of relative positions determined by the setting of the manually settable member.

11. In a mechanism for controlling an instrumentality, a cyclometer having a pair of related, relatively and independently movable, intermittently advanced counters adapted, by virtue of different relative positions, to indicate a predetermined fixed and definite plurality of different conditions; elements respectively settable each in different positions to sense by their relative positions any desired one of said plurality of different relative counter positions; settable means, including solely one rotatable indicator member, manually settable in different positions for indicating all of said relative counter positions; means connecting said member to said elements to adjustably move the latter at different rates respectively; and means including other elements respectively cooperating with said settable elements and including means independently positioning said other elements respectively by said counters for exercising a control over said instrumentality when the counters and other elements come to the particular set of relative positions determined by the setting of the manually settable member.

12. In a mechanism for controlling an instrumentality, a cyclometer having a pair of related, relatively and independently movable counters adapted, by virtue of different relative positions, to indicate a predetermined fixed and definite plurality of different conditions; contacts respectively settable each in different positions to sense by their relative positions any desired one of said plurality of different relative counter positions; a rotatable member manually settable in different positions all within a single 360° arc to correspond to all of said relative counter positions; means for gearing said member to said contacts in different ratios respectively; and means including other contacts respectively cooperating with said settable contacts and including means independently positioning said other elements respectively by said counters for switching a circuit to control said instrumentality when the counters and other contacts come to the particular set of relative positions determined by the setting of the manually settable member.

13. A mechanism for controlling an instrumentality, comprising a cyclometer or the like having a pair of related, relatively and independently movable counters provided with indicia, said counters being adapted to occupy as many different relative positions as the product of the number of indicia they carry; elements respectively settable each in different positions to sense any desired one of said different relative counter positions; a rotatable member manually settable in different positions within a single 360° arc, corresponding to all the different relative positions of the counters; means for gearing said member to said elements in different ratios respectively; and means including other elements respectively cooperating with said settable elements and including means independently positioning said other elements respectively by said counters for exercising a control over said instrumentality when the counters and other elements come to the particular set of positions determined by the setting of the manually settable member.

LUCIEN C. WUISCHPARD.
